(Continued)

Primary Examiner — Cynthia M. Chin

(74) Attorney, Agent, or Firm — Schott P.C.

(57) **CLAIM**

The ornamental design for a propulsion unit as shown and described.

DESCRIPTION

1. Propulsion unit

1.1 : Bottom

1.2 : Front

1.3 : Perspective

1.4 : Left

1.5 : Back

1.6 : Right

1.7 : Top

The design is a propulsion unit intended for boat propulsion. The broken lines define the bounds of the claimed design and form no part thereof.

1 Claim, 7 Drawing Sheets
